United States Patent Office

Des. 195,344
Patented June 4, 1963

195,344

EGG BEATER OR SIMILAR ARTICLE

Henning Waldemar Lindahl, Asmundtorp, Sweden

Filed Jan. 30, 1962, Ser. No. 68,570

Term of patent 14 years

Claims priority, application Sweden July 31, 1961

(Cl. D44—1)

FIG. 1 is a front perspective view of an egg beater or similar article showing my new design; and

FIG. 2 is an elevational view taken from the right of FIG. 1.

I claim:

The ornamental design for an egg beater, or similar article, as shown.
